UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

BUFFER MECHANISM FOR DIAPHRAGM FACE PLATES.

Application filed October 24, 1927. Serial No. 228,317.

Upper buffer mechanisms are used to keep the diaphragm face plates of adjacent passenger train cars in contact under all service conditions. The face plate must be permitted 5 to move longitudinally, laterally and/or obliquely relative to its normal position on the car. It must be permitted to move laterally of itself (i. e. longitudinally of the car) to accommodate the draft gear movements and must move longitudinally of itself 10 so that when one car swings more than its adjacent car the friction between the face plates will not tear either of them from their attachments. Furthermore, the face plate 15 must move obliquely when the cars are moving on a curved track. The face plate may, of course, make all of these movements consecutively or simultaneously.

My invention relates to devices which 20 yieldingly permit the face plate to make such movements and which have a tendency to return the face plate to its normal position and which do return it to such normal position when permitted to do so.

25 An object of the invention is to provide such a device which is simple and economic to manufacture and apply and which can be installed, inspected, repaired or replaced without entering the car or removing any 30 part thereof, not even the diaphragm of its face plate. Furthermore, the device is noiseless because all the parts are under pressure contact.

In the drawings:
35 Fig. 1 shows a typical application of my device to a railway car.

Fig. 2 shows the device in normal position.

Fig. 3 shows the device under maximum compression.

40 Fig. 4 shows the device when the diaphragm face plate has moved laterally of the car.

Fig. 5 shows the device when the diaphragm face plate has moved obliquely of 45 the car.

Fig. 6 shows a modified construction.

Figs. 7 and 8 show the bracket in plan and elevation, respectively.

Fig. 9 is a detail of the spring.
50 Fig. 10 is a modified form of spring.

Fig. 11 is a perspective view of the connecting member.

Figs. 12 and 13 show a modified form of the connecting member.

55 The usual parts of a railway passenger

train car are shown, such as the end wall 1, diaphragm 2 and diaphragm face plate 3.

The preferred form of my device comprises a leaf spring 4 (preferably semi-elliptical) or other resilient member secured to the end wall 60 of the car in any convenient manner or place, preferably adjacent the center line of the car. A bracket 5 is secured to the diaphragm face plate preferably adjacent the center line of the car in any convenient manner and connecting members 6 attach the outer ends 65 respectively of the spring to the bracket. This connecting member is pivotally attached to the spring and also pivotally connected to the bracket to allow for the various movements 70 of the device in service. I prefer to provide some stop arrangement to limit the amount of movement of the face plate toward the car to prevent any of the component parts of the device from being broken due to excessive 75 compression of the device.

When the diaphragm face plate moves laterally of the car, as shown in Fig. 4, one portion (7) of the semi-elliptical spring is under bending stress, while the other portion (8) 80 of the spring is distorted.

When the diaphragm face plate moves obliquely relative to the car, as shown in Fig. 5, one portion (9) of the spring is under bending stress, while the other portion (10) of 85 the spring is distorted.

Fig. 6 shows a modified construction whereby the spring 11 is made of two quarter elliptic springs instead of one semi-elliptic spring which may or may not be a mechanical 90 expedient.

Figs. 7 and 8 show details of the bracket which is preferably attached to the face plate to pivotally connect the two connecting members to the face plate. A stop 12 is preferably cast integral with this bracket 5 to restrict the movement of the face plate toward the car.

Fig. 9 shows a typical semi-elliptic spring of the preferred form provided with a flat 100 portion 13 for attachment to the car wall (or face plate) and with the cylindrical end portions 14 to provide a pivotal attachment to the connecting member.

Fig. 10 shows a semi-elliptic spring 4 with 105 an auxiliary leaf 15 positioned inside of the main leaf. This auxiliary leaf increases the resistance and resiliency of the spring when one portion of the spring is distorted, as shown at 8 in Fig. 4, and at 10 in Fig. 5. An 110

auxiliary leaf 16 may be positioned on the outside of the spring, as shown in Fig. 1, so as to increase the strength and resiliency of the spring when it is under bending stress, as shown in Fig. 3 or at 7 in Fig. 4. It may be desirable to use either or both of the auxiliary leaves 15—16.

Fig. 11 shows a perspective view of the connector 6 with the cylindrical end 17 to accommodate a pin for attachment to the bracket. This construction also has spaced apart jaws 18 at the other end to shroud the end of the spring and provide a pivotal connection therewith.

15 Figs. 12 and 13 show a modified form of the attachment of the connector to the spring wherein the end 19 of the spring 4 is split to accommodate eye 20 of the connector 6.

20 Turnbuckles 21 may be provided if desired for adjustment of the length of the connecting members 6 to position the diaphragm face plate in the center of the car and to increase or decrease the tension on the springs.

25 The spring may be attached to the car end wall element, as shown, or to the diaphragm face plate element if desired, and still come within the scope of the invention.

I claim:

1. In a railway car comprising an end wall element, a diaphragm face plate element movable longitudinally, laterally and obliquely from its normal position; the combination of a leaf spring having its middle portion attached to one of said elements, a bracket attached to the other of said elements, and two members, each member having its outer end pivotally connected to the outer end of the leaf spring and with its inner end pivotally connected to the opposite ends respectively of said bracket.

2. In a railway car comprising an end wall element, a diaphragm face plate element movable longitudinally, laterally and obliquely from its normal position; the combination of a leaf spring having its middle portion attached to one of said elements, two members,

each member having its outer end pivotally connected to the outer end of the leaf spring and with its inner end pivotally connected to the other of said elements, and means to restrict the movement of said face plate toward said end wall.

3. In a railway car comprising an end wall element and a diaphragm face plate element movable longitudinally, laterally and obliquely from its normal position; the combination of a leaf spring having its middle portion attached to one of said elements, and two members, each member having its outer end pivotally connected to the outer end of the leaf spring and with its inner end pivotally connected to the other of said elements, one of said members provided with means to adjust its length.

4. In a railway car comprising an end wall element and a diaphragm face plate movable longitudinally, laterally and obliquely from its normal position; the combination of a leaf spring having its middle portion attached to said end wall, a bracket attached to said face plate provided with a stop, and two members, each member having its outer end pivotally connected to the outer end of the leaf spring and with its inner end pivotally connected to said bracket, said stop arranged to engage said end wall upon a predetermined movement of the face plate toward the car.

5. In a railway car comprising an end wall element, and a diaphragm face plate element movable longitudinally, laterally and obliquely from its normal position; the combination of a leaf spring having its middle portion attached to one of said elements adjacent the center line of the car, a bracket attached to the other of said elements adjacent the center line of the car, and two members, each member having its outer end pivotally connected to the outer end of the leaf spring and with its inner end pivotally connected to said bracket.

ARTHUR E. SMALL.
